UNITED STATES PATENT OFFICE

2,004,705

UPHOLSTERY METHOD

Allister S. Mitchell, Detroit, Mich., assignor to
National Automotive Fibres, Inc., Oakland,
Calif., a corporation of Delaware

Original application February 19, 1930, Serial No.
429,708. Divided and this application March
5, 1931, Serial No. 520,360

13 Claims. (Cl. 112—262)

This invention relates particularly to a method of manufacturing upholstery, and more particularly to a novel mechanism and method for forming the seams of multi-pleat upholstery.

5 The primary object is to provide an improved method which will facilitate the formation of seams in stuffed, multi-pleat, or pleated, upholstery. Upholstery of the kind described usually comprises a main or cover fabric, and
10 a lining fabric united by parallel seams and divided thereby into pleat-fullnesses which are stuffed with batts.

The present application constitutes a division of my application, Serial No. 429,708, filed February 19, 1930.

The improved method for manufacturing upholstery of the kind described is preferably practiced by employing a machine which embodies one form of the invention and comprises a frame
20 having a vertically adjustable cross-head which carries a series of horizontally adjustable sewing-heads equipped with sewing-needles; looper-bars which co-operate with the sewing-needles to form chain-stitch seams in nested seam-ridges, formed in the main, or cover, and lining fabrics of the upholstery, the stitches passing through two thickness of one fabric and through a single thickness of the other; mechanism for feeding the main, or cover, and lining fabrics
25 continuously through the machine; mechanism for advancing cotton-batts through the machine between the cover and lining fabrics, the feeding means for the batts being stopped at intervals to space the batts between adjacent sections of
30 the upholstery which are to be severed from each other; pneumatic means co-acting with ridge-bars for forming the seam-ridges and intervening depressed pleats, or pipes, in the cover fabrics; means including creaser-bars for forming the
35 40 seam-ridges in the lining fabric; and driving means whereby a cyclic operation of the machine is obtained.

The sewing-heads of the machine, which is illustrated in the accompanying drawings and
45 which embodies the present invention, are not provided with looper-needles in accordance with the construction employed in the co-pending application of Allister S. Mitchell, Serial Nos. 347,935 and 427,205, filed March 18, 1929, and
50 Feb. 10, 1930, respectively. Instead, there are provided looper-bars, or needles, actuated and supported by mechanism which is disposed between the paths along which the lining fabric and the batts are advanced to the sewing-heads,
55 housing members being provided for the looper-

bars and arranged so that they provide spaces between the batts and the lining fabric wherein the looper-bars travel in substantially elliptical paths and co-operate with the sewing-needles. The housing members for the looper-bars are carried by the lining-creasers and their upper surface guide portions of the lining-fabric in such manner that a single thickness thereof is united with two thicknesses of the cover fabric at each seam.

10 The forward ends of the ridge-bars for forming the ridge-seams in the cover fabric are preferably provided with tips which are readily replaceable in the event they are broken or deformed during the operation of the machine.

15 The invention is illustrated in a preferred embodiment in the accompanying drawings, in which:—

Fig. 1 is a broken longitudinal vertical sectional view of an upholstery-making machine embodying the invention; Fig. 2, an enlarged broken plan view of the forward end of one of the ridge-bars provided for forming seam-ridges in the cover fabric; Fig. 3, a broken vertical sectional view taken as indicated at line 3 of Fig. 2; Fig. 4, a 20 broken vertical sectional view showing the looper-bar taken as indicated at line 4 of Fig. 13; Fig. 5, a perspective view (partly broken and partly in section) of a ridge-seam and the pleat fullnesses or outer side of it, the looper- 25 bar and sewing-needle being shown to illustrate the manner in which they cooperate to secure, or unite, one thickness of lining fabric with two thicknesses of cover fabric; Fig. 6, a broken longitudinal vertical sectional view showing the arrangement of the lining-creasers, the looper-bars and their housings, and the means for actuating the looper-bars; Fig. 7, a view similar to Fig. 6 but showing the looper-bar housing in section and the cover-plate for the looper-bar 30 actuating means removed; Fig. 8, a broken plan view of one of the looper-bars; Fig. 9, a plan view of one of the housing members provided for the looper-bars; Fig. 10, a broken rear elevational view of a suspension for one of the looper bars; Fig. 11, a broken plan sectional view taken as indicated at line 11 of Fig. 6; Fig. 12, a front elevational view of a lining-creaser, ridge-bar, 45 looper-bar, and looper-bar housing; and Fig. 13, a broken front vertical sectional view taken as indicated at line 13 of Fig. 1, showing the construction of the sewing-heads and the manner in which the sewing operations are performed, a cross-bar supporting the sewing-heads having been omitted to permit illustration of the form- 50 55

ing rolls which engage the outer surfaces of the lining fabric.

In the embodiment selected for illustrating the invention, A designates the main frame of a machine which is equipped near its front end with a vertically adjustable cross-head A', the frame being provided with members A² and A³; B, a suction conveyor device mounted in the bed of the machine and adjustably supported on the cross-members A² and A³, said conveyor having associated therewith ridge-bars B' which serve to produce seam-ridges in the main fabric; C, a series of sewing mechanisms mounted on the cross-head A' and laterally adjustable thereon to enable the width of the pleats to be varied, the sewing mechanisms being actuated by a common shaft C'; D, D', a pair of feed-rolls through which the upholstery is delivered from the machine; E, a forming roll disposed back of and carried by the lower portion of the adjustable cross-head A'; said forming roll comprising longitudinally adjustable frustro-conical rollers or collars E' forming grooves through which the ridge-bars B' extend; F, a series of lining-creasers adjustably mounted on a transverse bar F' carried by the bed; G, G', a main pair of batt-feeding rolls; H, H', an auxiliary pair of batt-feeding rolls, these rolls being periodically arrested to cause severance of the batts; J, a shearing device upon which the batts are severed when the auxiliary rolls H and H' are stopped; K, a deflector roll whose function is to direct the batts between the rolls G and G' when the feed is resumed; L, the main cover or finish fabric, which is led over the suction conveyor B to ride on the ridge-bars B'; M, lining fabric being led downwardly and forwardly in the manner shown; N, the strip of batting being led through the feed rolls G and G'; and P, an endless conveyor which carries the batts to the auxiliary feed rolls, having its front portion supported on standards P' mounted on the machine.

The above described mechanisms are driven in timed relation in substantially the same manner and have the same functions as shown and described in the above co-pending applications and, therefore, need not be described in detail in this application.

However, the function of the shaft C' differs somewhat from the function of the corresponding shaft shown and described in the last mentioned co-pending application, as in the present invention the sewing mechanisms C do not include looper-needles and means for actuating them, although in all other respects the sewing mechanisms C are preferably identical in construction and operation with similar mechanisms shown and described in the last mentioned co-pending application.

It may be mentioned that the sewing mechanisms C are pivotally suspended from brackets 17 which are adjustably mounted on the cross-head A' and that the actuating shaft C' is also journaled in said brackets. The sewing-needles are designated 18. They are actuated by levers 18^a which swing in a transverse plane. The sewing thread is designated 18^b.

In machines embodying the present invention, the looper-needles are preferably supported and operated independently of the sewing-mechanisms C, although they are actuated in synchronism. The looper-needle, shown in Fig. 7, associated with each sewing-head is designated 19 and is preferably formed integral or attached to a looper-bar 19^a disposed within a housing member

19^c. The looper-needle thread is designated 19^b.

As best shown in Figs. 6 and 7, the housing members 19^c are preferably formed integral with, or rigidly secured to the lining-creasers F, and each looper-bar 19^a has its back end slidably journaled in a block 19^d connected by a link 19^e to a lug 19^f depending from the transverse bar F'. A lever 19^g is provided for each looper-bar 19^a and one end thereof is pivotally connected to the looper-bar, the lever 19^g being fixed to a shaft 19^h extending transversely and positioned above the lining-creasers F. The shaft 19^h is provided with a lever 19^k operatively connected by an adjustable arm 19^m with an eccentric 19ⁿ actuated by a shaft 19° extending parallel to the shaft 19^h. Obviously, when the shaft 19° is rotated, the eccentric 19ⁿ will oscillate the shaft 19^h to reciprocate the looper-bars 19^a through the medium of the levers 19^g.

19^p designates a series of eccentrics mounted upon and actuated by the shaft 19°, each eccentric 19^p being operatively connected with a looper-bar 19^a by an arm 19^s. Each arm 19^s is provided with a pin 19^t engaging a slot 19^v in the associated looper-bar. The arrangement is such that when the shaft 19° is rotated, the looper-bars 19^a will be actuated in such manner that the looper-needles 19 will travel in substantially elliptical paths.

It will be noted that the shafts 19^h and 19° are positioned intermediate the paths along which the lining fabric and the cotton-batts travel to the sewing mechanisms C.

The lever 19^g and the arm 19^s project through relatively wide shallow grooves 19^x formed in side surfaces of the lining-creasers F, the grooves 19^x being provided with cover-plates 19^y (see Figs. 7 and 11).

As the fabrics move through the machine, the lining fabric M has formed therein seam-ridges 20 (see Figs. 5 and 13), and the main fabric L has formed therein U-shape seam-ridges 21 which become nested with the seam-ridges 20. Each seam-ridge 20 formed in the lining fabric M comprises a substantially flat seam portion 20^a positioned adjacent and in contact with one wall or leg of the associated seam-ridge 21, formed in the main fabric L. The sections or pleats of the lining fabric M that lie between the seam portions 20^a are designated 20^b and are held at an angle to the main fabric L during the sewing operation.

As best shown in Fig. 13, each section 20^b extends from the upper edge of a seam portion 20^a to the bottom edge of the adjacent seam portion 20^a. The lining fabric M is shaped in this manner by the forming-roll E' and by laterally adjustable shoes 22 carried by the cross-head A'. When the lining fabric M is disposed in this manner with respect to the main fabric L, it is obvious that the sewing-needles 18 will each pass through a single thickness of the lining fabric and through two thicknesses of the main fabric. As shown, the forward ends of the housing members 19^c are substantially triangular in cross-section and are arranged in such manner that they hold the cotton-batts spaced from the seam-ridges and provide spaces wherein the sewing-needles 18 may cooperate with the looper-needles 19 without becoming entangled with the batts, a wall of each housing member being apertured to permit passage of the associated sewing-needle therethrough.

In the sewing operation, each sewing-needle and its associated looper-needle cooperates to produce a double thread chain-stitch, which is 75

familiarly known in the trade as a "chain lock stitch".

The looper-thread ^{19b} advances to the looper-needle through a groove ²³ provided in the associated lining-creaser ^F, the looper-thread being withdrawn from a spool ²⁴ mounted on the standard ^{P'}. From the groove ²³, the looper-thread passes through a groove ²⁵ cut in the upper surface of the looper-bar, the thread being retained in the groove by pins ^{25a} (see Fig. 8) extending transversely of the groove. From the groove ²⁵, the looper-thread passes through holes ²⁶ and ²⁷ drilled in the forward end of the looper-bar and then through a hole ²⁸ drilled in the forward end ¹⁵ of the looper-needle (see Fig. 4). The looper-needle ¹⁹ is formed by providing a U-shaped end at the forward end of the looper-bar, the construction being such that the forward end of the looper-needle points in the opposite direction to ²⁰ that in which the forward end of the looper-bar points.

The sewing-thread ^{18b} is preferably advanced to the sewing-needle ¹⁸ in the same manner as it is advanced to the corresponding sewing-needle shown and described in the last-mentioned co-pending application, the sewing-thread being trained through a hole drilled in the forward end of the sewing needle.

The mechanism in advance of the lining-creasers ^F for advancing the lining and main fabrics, and the cotton-batts, and the mechanism in advance of the lining creasers ^F for forming seam-ridges and intervening pleat-fullnesses in the main, or cover, fabric are substantially identical with similar mechanisms shown and described in the last mentioned co-pending application and need not be described in detail.

The lining creasers ^F, the forming roll ^E and the forward ends of the ridge-bars ^{B'} are of different construction and must be described in more detail.

The suction conveyor ^B (Fig. 1) comprises a hollow rectangular frame ³⁰ which is open at its top and is connected to an exhaust pipe ³¹; and ⁴⁵ ^{30a} a foraminous belt which passes about rollers ^{30b} and ^{30c} journaled in the frame, the belt being arranged to travel over the open top of the frame.

The suction pipe ³¹ connects with the intake portion of a fan or blower and is operated by an independent motor, not shown.

The ridge-bars ^{B'} extend through grooves formed between the adjustable shoes ²² carried by the cross-head ^{A'}. At their forward ends, the ridge-bars ^{B'} are provided with replaceable tips ³² which fit in slots ³³ cut through the ridge-bars (see Figs. 2 and 3), the tips ³² having notches ³³ through which the sewing-needles ¹⁸ travel. The ridge-bars ^{B'} are preferably T-shaped in cross-section and their forward ends are connected for lateral adjustment upon the cross-bar ^{A²}. Screws ³⁴, provide means for rigidly securing the tips ³² in the slots ³³ (see Fig. 2). This construction is advantageous as it permits the tips to be readily replaced if they are broken or deformed during the operation of the machine.

The lining creasers ^F are disposed over the ridge-bars ^{B'} and are provided with Y-shaped portions ³⁵ at their back ends, which portions have upper inclined surfaces ^{35a} for guiding the edges of the batts onto inclined surfaces ^{19c} formed upon the housing members ^{19c} and upon inclined surfaces ^{35b} formed on the sides of the lining-creasers ^F opposite to the sides thereof to which the housing members ^{19c} are secured (see Figs. 6, 7 and 12). These surfaces ^{19c} and ^{35b}

serve to properly guide the batts as they approach the forming-roll ^E. The lining-creasers are also provided with beveled front edges ^{35a} which extend into the grooves ³⁶ of the forming-roll ^E.

Fig. 13 illustrates the forming-roll ^E, the sewing-heads ^C and the shoes ²² in their functionally operative positions with respect to the ridge-bars ^{B'}. When the forming-roll ^E is in its functionally operative position with respect to the ridge-bars ^{B'}, each of the rollers ^{E'} depresses the batt passing underneath it so that one edge of the batt is urged downward to engage a cam surface ³⁷ provided upon the associated housing member ^{19c} and is further depressed thereby so that it ¹⁵ will ride along the lower surface of the housing member (see Figs. 6, 9 and 13). The remaining portion of the top surface of each batt is held depressed between the ridge-bars ^{B'} by the associated roller ^{E'}, and the associated shoe ²² which ²⁰ has an inclined lower surface conforming to the taper of the roller ^{E'}.

The operation of the machine may be described briefly: Assuming a partial vacuum obtains in the suction conveyor through the action of a blower, this conveyor operates to feed the main, or cover, fabric through the machine and form it into seam-portions and intervening pleat-fullnesses, the main, or cover, fabric being properly gathered and shaped over the ridge-bars ^{B'} ³⁰ by the suction exerted through the belt ^{30a}. The batts are carried by the batt-conveyor ^P to the auxiliary batt-feeding-rolls ^H and ^{H'}, from which the batts pass over the shearing device ^J and thence through the main batt-feeding rolls ³⁵ ³⁵ G and G'. The lining fabric ^M has seam-ridges ³⁸ preparatory formed therein in passing over spaced collars, not shown. These seam-ridges persist, more or less, until they encounter the creasers ^F which direct them properly into the ⁴⁰ grooves of the forming-rolls ^E. In passing between the forming-roll and the pneumatic conveyor, the seam-ridges of the two fabrics become properly nested and the batts become properly positioned in the pleats as they are formed. The ⁴⁵ seams pass underneath the sewing-mechanisms, each of which operates in such manner that a single thickness of the lining-fabric is sewed to two thicknesses of the main, or cover, fabric. The upholstery then passes on through the front ⁵⁰ feed-rolls ^D and ^{D'}, which are preferably geared to speed slightly faster than the other feed devices. The batts are severed at intervals by the severing device ^J in a manner more fully described in the last mentioned co-pending application, so that the lining and cover fabrics may be subsequently severed at the same points to divide the upholstery into units.

The foregoing detailed description has been given for clearness of understanding only, and ⁶⁰ no unnecessary limitation should be understood therefrom, but the appended claims should be construed as broadly as permissible, in view of the prior art.

What I regard as new, and desire to secure by Letters Patent, is:

1. In the manufacture of pleated upholstery, the steps which comprise: feeding fabrics and batts with batts disposed between the fabrics, forming seam-portions in the fabrics, holding ⁷⁰ each batt spaced from one side of a seam-portion to provide interior sewing spaces, and engaging loops of the sewing thread with looper thread loops formed in said sewing spaces.
2. In the manufacture of pleated upholstery, ⁷⁵

- the steps comprising: advancing a lining fabric, advancing a main fabric and employing fluid pressure to form seam-ridges therein, each seam-ridge including two thicknesses of said main fabric, and uniting said lining fabric to said seam-ridges by stitches extending through one thickness solely of said lining fabric and through said two thicknesses of main fabric in said seam-ridges.
10. 3. A method as specified in claim 2, characterized by passing the sewing thread through the fabrics and engaging the loops of the sewing thread with a looper thread lying between the fabrics.
15. 4. In the manufacture of pleated upholstery, the step which comprise: advancing a lining fabric and a main fabric, subjecting one of said fabrics to fluid pressure as it advances to form seam-ridges and intervening pleat-fullnesses 20 therein, uniting said fabrics by stitches of a sewing thread passed therethrough from the outer side of one of them, and engaging loops formed in said sewing thread by loops of a looper thread lying between the fabrics.
25. 5. In the manufacture of pleated upholstery, the steps which comprise: feeding fabrics and batting with the batting disposed between the fabrics, forming a plurality of longitudinally extending seam-portions, holding the batting spaced from one side of the seam-portion to provide interior sewing spaces, forming loops of 30 sewing thread and engaging said loops with looper thread loops formed in said sewing spaces.
35. 6. In the manufacture of pleated upholstery, the steps which comprise: feeding fabrics and bats with the bats disposed between the fabrics, forming seam-portions in the fabrics, holding each bat spaced from one side of a seam-portion to provide interior sewing spaces, and simultaneously sewing the fabrics to each other between the bats by passing the sewing thread through 40 the fabrics, forming loops of sewing thread and engaging said loops with looper thread loops formed in said sewing spaces.
45. 7. In the manufacture of pleated upholstery, the steps which comprise: advancing a lining fabric and a main fabric with bats disposed therebetween, forming seam-ridges between the bats, then uniting said fabrics by stitches of a sewing thread passed therethrough from the outer side of one of them and engaging loops formed in said sewing thread by loops of a looper thread lying between the fabrics.
50. 8. In the manufacture of pleated upholstery, the steps which comprise: advancing a lining fabric and a main fabric with bats disposed therebetween, subjecting one of said fabrics to fluid pressure as it advances to form seam-ridges between the bats, uniting said fabrics by stitches of a sewing thread passed therethrough from the 55 outer side of one of them, and engaging loops formed in said sewing thread by loops of a looper thread lying between the fabrics.
5. The method of forming upholstery which comprises feeding two sheets of fabric into superimposed relationship, locating a plurality of stitch forming instrumentalities in spaced relation including loopers positioned between said sheets, and causing said instrumentalities to sew said sheets together along spaced lines so that the lines of stitching are completed between the sheets by said loopers.
10. The method of forming upholstery which comprises feeding two sheets of fabric into superimposed relationship, forming a series of parallel folds in one of said sheets, locating stitch-forming instrumentalities in operative relation to said folds including loopers positioned between said sheets, and causing said instrumentalities to sew said folds to the other sheet so that the lines of stitching are completed between the sheets by said loopers.
15. The method of forming upholstery which comprises feeding two sheets of fabric into superimposed relationship, feeding a plurality of strips of padding material between said sheets, locating in spaced relation a plurality of stitch-forming instrumentalities including loopers positioned between said sheets and between said padding strips, and causing said instrumentalities to sew said sheets together along parallel lines between said padding strips so that the lines of stitching are completed between the sheets by said loopers.
20. The method of forming upholstery which comprises feeding two sheets of fabric into superimposed relationship, feeding parallel strips of padding material between said sheets, forming a series of parallel folds in one of said sheets between said padding strips, locating stitch-forming instrumentalities in operative relation to said folds, said instrumentalities including loopers positioned between said sheets, and causing said instrumentalities to sew said folds to the other sheet so that the lines of stitching are completed between the sheets by said loopers.
25. The method of forming upholstery which comprises feeding two sheets of fabric into superimposed relationship, forming a series of parallel folds in one of said sheets, guiding the other sheet into engagement with said folds, locating a plurality of stitch-forming instrumentalities in operative relation to said folds, said instrumentalities including loopers positioned between said sheets, and causing said instrumentalities to sew said sheets together along said folds so that the lines of stitching extend through both thicknesses of said folds and through one thickness only of the other sheet and are completed between the sheets by said loopers.
30. The method of forming upholstery which comprises feeding two sheets of fabric into superimposed relationship, forming a series of parallel folds in one of said sheets, guiding the other sheet into engagement with said folds, locating a plurality of stitch-forming instrumentalities in operative relation to said folds, said instrumentalities including loopers positioned between said sheets, and causing said instrumentalities to sew said sheets together along said folds so that the lines of stitching extend through both thicknesses of said folds and through one thickness only of the other sheet and are completed between the sheets by said loopers.
35. The method of forming upholstery which comprises feeding two sheets of fabric into superimposed relationship, forming a series of parallel folds in one of said sheets, guiding the other sheet into engagement with said folds, locating a plurality of stitch-forming instrumentalities in operative relation to said folds, said instrumentalities including loopers positioned between said sheets, and causing said instrumentalities to sew said sheets together along said folds so that the lines of stitching extend through both thicknesses of said folds and through one thickness only of the other sheet and are completed between the sheets by said loopers.
40. The method of forming upholstery which comprises feeding two sheets of fabric into superimposed relationship, forming a series of parallel folds in one of said sheets, guiding the other sheet into engagement with said folds, locating a plurality of stitch-forming instrumentalities in operative relation to said folds, said instrumentalities including loopers positioned between said sheets, and causing said instrumentalities to sew said sheets together along said folds so that the lines of stitching extend through both thicknesses of said folds and through one thickness only of the other sheet and are completed between the sheets by said loopers.
45. The method of forming upholstery which comprises feeding two sheets of fabric into superimposed relationship, forming a series of parallel folds in one of said sheets, guiding the other sheet into engagement with said folds, locating a plurality of stitch-forming instrumentalities in operative relation to said folds, said instrumentalities including loopers positioned between said sheets, and causing said instrumentalities to sew said sheets together along said folds so that the lines of stitching extend through both thicknesses of said folds and through one thickness only of the other sheet and are completed between the sheets by said loopers.
50. The method of forming upholstery which comprises feeding two sheets of fabric into superimposed relationship, forming a series of parallel folds in one of said sheets, guiding the other sheet into engagement with said folds, locating a plurality of stitch-forming instrumentalities in operative relation to said folds, said instrumentalities including loopers positioned between said sheets, and causing said instrumentalities to sew said sheets together along said folds so that the lines of stitching extend through both thicknesses of said folds and through one thickness only of the other sheet and are completed between the sheets by said loopers.
55. The method of forming upholstery which comprises feeding two sheets of fabric into superimposed relationship, forming a series of parallel folds in one of said sheets, guiding the other sheet into engagement with said folds, locating a plurality of stitch-forming instrumentalities in operative relation to said folds, said instrumentalities including loopers positioned between said sheets, and causing said instrumentalities to sew said sheets together along said folds so that the lines of stitching extend through both thicknesses of said folds and through one thickness only of the other sheet and are completed between the sheets by said loopers.

ALLISTER S. MITCHELL.
